UNITED STATES PATENT OFFICE.

KRISTEN ANDREAS THORSEN, OF GRENOBLE, FRANCE.

APPARATUS FOR COMMUNUTING, REFINING, AND TRITURATING PAPER OR CARD-BOARD PULPS.

Application filed February 10, 1920. Serial No. 357,748.

(GRANTED UNDER THE PROVISIONS OF THE ACT OF MARCH 3, 1921, 41 STAT. L., 1818.)

To all whom it may concern:

Be it known that I, KRISTEN ANDREAS THORSEN, a subject of the Kingdon of Norway, and resident of Grenoble, France (post-office address Rue Aubert Dubayet No. 3), have invented a new and useful Apparatus for Communing, Refining, and Triturating Paper or Cardboard Pulps, for which I have filed an application in 10 France on Feb. 8, 1919, Patent No. 498,216, and which improvements are fully set forth in the following specification.

This invention relates to an apparatus for communing, triturating, dividing, 15 shortening and reducing the thickness of fibres of various materials that can be used for the manufacture of all kinds of paper and cardboard. These fibres are held in suspension in a certain quantity of water.

20 Apparatus of the character specified is generally known in the industry as a "rag engine," and is generally constituted by a cylinder provided with ribs having cutting edges of more or less extent. This cylinder 25 is mounted on a central shaft, the ends of which rotate in fixed brackets on levers adjusted by means of a suitable regulating device. Below the cylinder, sometimes above it, and generally near the vertical axis, is arranged a fixed block also provided with 30 ribs with cutting edges. This block, called in the industry the "knife-plate," is firmly secured to a suitable casing so that its ribbed surface can come into perfect contact with 35 the periphery of the rotating cylinder. In the manufacture of paper, the latter is pressed against the plate with a greater or less intensity, for variable periods of time, according to the quality of the paper to be 40 obtained and to the nature of the material to be ground. It is well known that the intensity of contact between the cylinder and the plate, and the precision with which the said contact is obtained, are of the 45 greatest importance for the good manufacture of the paper. This precision has been difficult to obtain and to control up to now on account of the great weight of the cylinder, and of the pull of the belt which transmits movement to it, as well as of the

almost complete absence of elasticity in the 50 parts utilized.

It has been sought to eliminate the said drawback and at the same time to simplify the transmission of movement to the cylinder by causing the latter to rotate in fixed 55 brackets and by making the plate movable, by exerting on it an adjustable and controllable pressure. This has led to various constructions, all of which suffer from the same drawback, viz: the difficulty experienced in mounting a movable plate in a fixed support in such a manner that the material to be triturated cannot penetrate into the support and become thickened therein, 60 thus injuriously affecting the mobility of 65 the said plate.

In the present invention, the difficulty in question has been done away with by introducing the pulp under the plate, so that the pulp then follows the passage formed on 70 the one hand by the outer surface of the carrier which supports the plate, and on the other hand by the bottom or the wall of the vat, the ribbed surface of the plate being in contact with the cylinder. The pulp 75 is thereupon seized by the periphery of the cylinder, the direction of movement of which is opposite to that of the pulp. The fibres are cut, reduced in thickness and shortened and are discharged by the periphery of the cylinder at the upper part of 80 the latter.

A second object of the present invention is the provision of a movable plate, the 85 space occupied by the plate constituting a conduit isolated from the outside by stuffing boxes on the shaft of the cylinder. This conduit is fed under pressure by a screw propeller or by a propeller of any other type. The pulp is introduced under pressure through the interstices of the cutting edges of the cylinder, in order to increase its supply and the speed of circulation in the rag or beating engine. In these 90 conditions, the cylinder must be mounted at 95 a high level in order that the slope of the conduit in which the pulp circulates from the outlet from the cylinder to the inlet of the propeller should be sufficient to give the

pulp a speed corresponding to the speed of the propeller.

The accompanying drawings show three arrangements of the plate and of the water tight plate chamber, forming the subject of the present invention.

Figure 1 is a longitudinal, vertical section through the movable part and the cylinder,

Figure 2 is a side elevation of the apparatus shown in Figure 1,

Figure 3 is a cross-section of the carrier for supporting the movable plate,

Figure 4 shows the rag engine in plan,

Figure 5 is a sectional view of the second arrangement, in which a screw propeller is utilized,

Figure 6 is a side elevation of Figure 5,

Figure 7 is a plan view of Figure 5,

Figure 8 is a longitudinal section of the third arrangement,

Figure 9 is a side elevation of Figure 8,

Figure 10 is a cross-section through the movable plate and the cylinder,

Figure 11 is a plan view of Figure 8.

The apparatus forming the subject of the present invention chiefly comprises a cylinder 1 provided with cutting ribs 2, mounted in fixed brackets 3 and driven by a pulley 4 with a belt, or direct by any desired motor.

Against the surface of the rotating cylinder and concentric with it, is forced with an adjustable pressure the movable plate 5 which is also provided with cutting ribs 2 and which oscillates freely about a horizontal axis constituted by a pair of pivot pins 6 which are secured directly to the plate carrier 5' at opposite ends thereof and are mounted to turn in bearings provided on the frame or body of the engine.

The pressure required to force the knife plate 5 against the cylinder is supplied, according to the construction illustrated in Figures 1 to 4, by means of a counterweight 7 which is adjustably mounted on the long

cross-arm of a T-shaped lever 8, whose stem is suitably hinged or pivoted at its lower end at 8' to the top portion of the carrier 5'; the said cross-arm extending over and beyond the carrier, while the other or short

cross-arm extends over the cylinder, as represented in Figure 4. The weight-carrying cross-arm has hinged to it the upper end of a threaded-rod 8² on which is rotatably mounted a collar 8³ associated with a hand wheel 8⁴. A spring 17 is interposed between this collar 8³ and a seat or housing 5² provided on the top of the carrier 5', and serves to transmit to the latter the pressure exerted by the weight 7; such pressure being trans-

mitted to said collar through the cross-arm and the rod 8², and being regulated by the adjustment of the weight, as will be understood, as well as by the tension of the spring which is itself controlled by means of the hand wheel 8⁴ and the collar. The weight

is retained in adjusted position on its cross-arm by means of a hand wheel 10 and rollers 11 (Figure 1), but can be removed from said arm and mounted on the other cross-arm when desired, as subsequently explained.

As it often happens that a mass of pulp or even a foreign body becomes entrained between the knife cylinder, which rotates at a high speed, and the knife-plate, the latter is moved very abruptly away from the former in consequence. This movement is deadened or cushioned by means of the spring 17,

so that the lever 8 and the weight 7 are not raised too quickly, which might easily cause breakage. Furthermore, when the engine is empty it is necessary to move the knife-plate away from the cylinder in order to avoid use-

less friction between them which would produce overheating in the absence of the water and pulp; and it is equally necessary to separate the plate and cylinder at the moment of charging so as to provide a passageway for the pulp and thus avoid excessively violent shocks. This separation may be effected

by shifting the weight 7 from the long cross-arm of the lever to the short cross-arm, which latter, as previously explained, overlies the cylinder. The free end of the stem of the lever and the portion of the carrier 5' to which it is hinged are provided with co-

acting integral tappets or lugs 18 (Figure 1) which are caused to engage each other when the weight 7 is transferred to the short cross-arm; and since the pressure of the weight will then be exerted at the opposite side of the axis of movement 6 of the carrier 5', the latter will thereupon be caused to swing or rock about such axis in a counter-

clockwise direction or away from the cylinder, carrying the knife-plate 5 with it.

The carrier is arrested at the desired point in this separating movement by means of a lever 19 fixed to one of the carrier pins 6 to turn therewith during the swinging movements of the carrier. This lever 19 is re-

cessed or seated at 19' to accommodate one end of a spring 22, the other end of which bears against an adjustable collar 21' mounted on a threaded rod 20 and provided with a hand wheel 20' regulating the tension of the spring; the lower end of rod 20 being pivoted to a bracket 20² mounted on a fixed part of the engine frame. The position of the collar and its hand wheel is previously

adjusted, by turning the hand wheel, in such a way that the spring 22 will yield just sufficiently to enable the swinging movement of the carrier to the extent necessary to provide the desired passage between the knife-plate and the cylinder.

In the construction represented in Figures 5 to 11, two levers 8^a carrying counterweights 7 are employed, one at each side of the engine. These levers are connected together at one end by a cross-rod or spindle

12 provided at its ends with sprockets 14 and adapted to be turned in one direction or the other by a hand wheel 13. The sliding weights 7 are suitably connected to 5 chains 15 which pass at one end over the sprockets 14 and at the other end over similar sprockets 14' at the opposite end of the levers 8^a, so that by turning wheel 13 both weights will be synchronously adjusted and the pressure exerted by both levers will be the same. The latter have depending threaded rods hinged to them, as in the first construction, which rods carry hand wheels 23 for the purpose of adjusting 10 the tension of springs 17^a interposed between said hand wheels and the recessed or cupped ends of a pair of lever arms 16^a fixed to short rock shafts 16 suitably journaled in the engine frame. The knife-plate 20 5, in this construction, is carried by a pair of lever arms 5^a fixed to the pivot pins 6 and which take the place of the carrier 5' in the first form; each arm 5^a being engaged by a tappet 9 fixed to the adjacent 25 rock shaft 16. The pressure of the counterweights 7 is exerted through the threaded rods and the springs 17^a on the lever arms 16^a, and is transmitted through said arms 16^a to the rock shafts 16, which are therefore 30 turned so as to cause their tappets 9 to press the plate-carrying arms 5^a toward the cylinder. The plate may be caused to move away from the cylinder simply by turning the hand wheels 23.

35 If desired, the construction just described may be simplified by omitting one of the levers 8^a and the parts immediately associated with it; in which case, the spindle 12 will also be omitted, and a single long rock 40 shaft will be employed in place of the two short rock shafts 16. This long rock shaft will be provided not only with the two tappets 9 of the short rock shafts, but also with a third tappet which will be located beneath the central portion of the knife-plate.

In the event of the pulp being very thick and consequently circulating with difficulty, a screw propeller 24, or a propeller of any other type, is provided as shown in Figures 5-7. This propeller is driven by the cylinder through the intermediary of pulleys 25 and of a belt 26 or direct by a motor. Its object is to force the pulp with a certain amount of pressure under the plate 55 and the cylinder, the latter being shut off from the outside by a hood 27 with stuffing boxes 28 through which pass the ends of the cylinder. The conduit 29 supplying the

pulp from the propeller to the cylinder is also closed in a tight manner. 60

The cylinder must be placed at a suitable level, so as to obtain a sufficient fall for giving a desired speed to the pulp between the upper outlet of the cylinder and the propeller. 65

I claim as my invention:—

1. In a pulp engine, the combination of a relatively-fixed knife cylinder; a knife-plate cooperative therewith; a movable carrier for the knife-plate mounted to swing toward and from the cylinder, and beneath which carrier the stream of pulp is introduced and caused to flow to the point where it is engaged by the coacting knives of the cylinder and plate; a pivotally-mounted, angular lever; a counterweight slidably mounted on one arm of said lever; and means, including a spring, for transmitting the pressure exerted by the weighted arm of the lever to the carrier so as to force the latter 80 and the knife-plate toward the cylinder. 75

2. In a pulp engine, the combination of a cylinder, a ribbed plate cooperative therewith, and a movable support for said plate submerged in the pulp in the engine; the side of the support remote from the ribs or the plate forming conjointly with the inner walls of the engine a channel for supplying the pulp between the cylinder and said plate. 90

3. In a pulp engine, the combination of a cylinder, a ribbed plate cooperative therewith, a movable support for said plate submerged in the pulp in the engine, and means for imposing a regulatable pressure against 95 said support so as to force it and the plate toward the cylinder; the side of the support remote from the ribs or the plate forming conjointly with the inner walls of the engine a channel for supplying the pulp between the cylinder and said plate. 100

4. In a pulp engine, the combination of a cylinder, a ribbed plate cooperative therewith, a movable support for said plate submerged in the pulp in the engine, a pivotally-mounted, angular lever, a counterweight slidably mounted on one arm of said lever, and means, including a spring for transmitting the pressure exerted by the weighted arm of the support to said support so as to force the latter and the ribbed plate toward the cylinder. 105
